(74) Attorney, Agent, or Firm — Hemisphere Law, PLLC;
Zhigang Ma**CLAIM**

The ornamental design for a cheese slicer as shown and described.

DESCRIPTION

FIG. 1 is a front, left, and top perspective view of a cheese slicer, showing my new design;
FIG. 2 is a rear, right, and bottom perspective view thereof;
FIG. 3 is a front view thereof;
FIG. 4 is a rear view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of an encircled area labeled "9" in FIG. 1.
The dot-dash broken lines shown in FIGS. 1 and 9 framing portions of the cheese slicer for enlargements purposes form no part of the claimed design.
